Franklin R. Chandlee

By Attorneys.

UNITED STATES PATENT OFFICE.

FRANKLIN R. CHANDELLE, OF ST. JOSEPH, MISSOURI.

GLAZIER'S HAMMER.

1,390,498.

Specification of Letters Patent. Patented Sept. 13, 1921.

Application filed May 27, 1921. Serial No. 473,060.

To all whom it may concern:

Be it known that I, FRANKLIN R. CHANDELLE, a citizen of United States, residing at St. Joseph, in the county of Buchanan, 5 State of Missouri, have invented certain new and useful Improvements in Glaziers' Hammers; and I do hereby declare the following to be a full, clear, and exact description of the invention, such as will enable others 10 skilled in the art to which it appertains to make and use the same.

This invention relates to glaziers' hammers and it has for its object to provide as an article of manufacture a hammer that 15 will effectually withstand the strains to which it is subjected in use and will at the same time be sufficiently economical of manufacture, to insure its commercial success.

It is a further object of the invention to 20 provide a hammer of this particular type, having a plurality of flat side faces at each end of its head that may be shifted to interchangeably lie flat against a pane of glass to facilitate driving of the glass retaining 25 points in whatever angle to the glass the hammer handle may be held and in which furthermore the driving may be accomplished with either end of the head, without shifting the hammer from the glass.

30 In the drawings:—

Figure 1 is a view showing the complete hammer in side elevation.

Fig. 2 is a central longitudinal section through the handle on the line 2—2 of Fig. 35 1, to include the middle portion of the head at one end of the handle and the chisel blade at the other end of the handle.

Referring to the drawings, the present 40 hammer includes a head, the end portions of which have the form of equilateral triangular prisms 5 and 6 respectively that are in axial alinement while the intermediate portion 7 of the head is cylindrical. The end faces 8 and 9 of the head are flat and at 45 right angles to the longitudinal axis of the head.

A handle 10 is provided and is formed with a slot 11 extending longitudinally through one end portion of the handle and 50 in this slot is disposed the end portions 12 of a metal strap, the intermediate portion of which is bent to fit snugly around the cylindrical intermediate portion 7 of the hammer head, but with sufficient looseness 55 to permit of rotation of this portion of the hammer head. The said intermediate por-

tion 13 of the metal strap, is cylindrical as shown and its edges are in close relation to the shoulders 14 that bound the cylindrical portion 7 of the hammer head, so that longitudinal movement of the hammer head with respect to the strap, is prevented. Rivets 15 are engaged through the handle and the overlapped end portions of the strap that are within the slot 11.

The butt end of the handle 10 is also slotted as shown at 16 to receive a chisel blade 17 that projects at one end from the slot, the blade being held in place by means of rivets 18.

In use, the hammer is disposed with a pair of prism faces of opposite end portions of its head flat against a pane of glass, at which time the pivotal connection of the handle with the head will permit the handle 75 to be swung toward and away from the glass during manipulation of the hammer, these faces of the head being thus readily held at all times snugly against the glass. Furthermore, by reason of the pivotal connection of the head with the hammer, the head quickly adjusts itself to bring a pair of faces against the glass in whatever position the head may have with respect to the glass when it initially contacts it.

The chisel blade at the butt end of the handle may of course be used for clenching or for whatever other purpose it may serve.

What is claimed is:

1. A glazier's hammer comprising a head, 90 a metal strap engaged about the head and in which the head is rotatable and a handle in which the strap is held, the head having a plurality of flat side faces parallel with its axis of rotation.

2. A glazier's hammer comprising a head having a plurality of flat, glass contacting side faces at each end and an intermediate cylindrical portion and a handle with which the cylindrical portion is rotatably connected.

3. A glazier's hammer comprising a head having a plurality of glass contacting side faces and an intervening cylindrical portion and a handle with which the cylindrical portion is rotatably connected.

4. A glazier's hammer comprising a head having a flat side face to rest against a pane of glass and having an integral extension, and a handle with which the extension is 110 connected for rotation on an axis parallel with said side face.

5. A glazier's hammer comprising a head having a flat side face to contact the glass and a cylindrical portion, the axis of which is parallel with said side face and a handle including a metal strap having a cylindrical portion in which the cylindrical portion of the head is rotatably mounted.

In testimony whereof, I affix my signature, in the presence of two witnesses.

FRANKLIN R. CHANDELLE.

Witnesses:

EDMUND G. CHANDELLE,
WM. JAS. EDELEN.
